UNITED STATES PATENT OFFICE

CHARLES F. THOLIN, OF ROCKFORD, ILLINOIS

WALL CABINET FOR TELEPHONES

Application filed July 12, 1930. Serial No. 467,468.

This invention relates to a wall cabinet for telephones suitable for hotels, apartments and homes, and wherever it is desired to conceal the phone and conserve space by eliminating the ordinary telephone stand.

The principal object of my invention is to provide a cabinet of this kind which is neat and attractive in appearance, compact and economical in construction, and easy to install and wherein the phone is entirely concealed and out of the way, but is easily and quickly accessible for use.

The salient feature of the cabinet of my invention consists in the provision of an outwardly swingable shelf for the phone and an outwardly swingable seat in combination therewith, the former being hinged on a vertical axis and the latter on a horizontal axis and so arranged with respect to one another that the phone is supported handily with reference to the seat and can be used without removal from the shelf by one sitting on the seat.

Another important feature of my invention consists in the provision of a suitable connection between the seat and shelf so that the seat is swung out in the opening of the door on which the shelf is provided, and vice versa. The seat is preferably counter-balanced for easy and smooth operation, and the connection between the seat and shelf is preferably such as to permit a certain amount of latitude for movement of the door independently of the seat when opened so that the door can be swung out of the way to make it handier in sitting down and rising from the seat.

The invention is illustrated in the accompanying drawings in which—

Figure 1 is a vertical section through the cabinet when closed;

Figs. 2 and 3 are vertical and horizontal sections showing the cabinet opened;

Fig. 4 is a fragmentary horizontal section on a slightly enlarged scale indicating how the door can be swung freely with reference to the seat;

Fig. 5 is a similar section but showing the door closed; and

Fig. 6 is a fragmentary vertical sectional detail taken on the line 6—6 of Fig. 5.

The same reference numerals are applied to corresponding parts throughout the views.

The cabinet 10 is illustrated as set in the wall 11 with the front thereof almost flush with the wall, so that the floor space in the room is saved thereby. A suitable ornamental molding 12 is provided around the cabinet opening for the sake of neat appearance. The cabinet is made sufficiently narrow to fit between the standardly spaced studding and may be fastened thereto or mounted in the wall in any other manner. The top 13 and bottom 14 of the cabinet are fastened suitably to the upright sides 15 and 16, and a back wall 17 is fastened to these other pieces. The phone box 18 is arranged to be mounted in the lower end of the cabinet on the back wall 17, and suitable brackets 19 are preferably also provided in the cabinet fastened to the back wall 17 above the box 18. This provides a convenient place for the telephone directory 20. The concealment of the box 18 and the provision of a place for storage of the telephone directory are naturally of considerable advantage, for obvious reasons, and it will now appear how the telephone 21 is also arranged to be concealed in the cabinet but in such a way that it is easily and quickly accessible and positioned handily for use.

The open front of the cabinet is arranged to be closed by a door 22 and seat panel 23 as indicated in Fig. 1. The door is above the seat panel and is hinged to the side 15 as at 24 to swing on a vertical axis. The seat panel 23, on the other hand, is hinged or trunnioned to the sides 15 and 16 as at 25, near the lower end thereof, to swing on a horizontal axis. The door 22 has a shelf 26 thereon suitably recessed as indicated at 27 to receive the telephone, the circular base of the phone fitting neatly in the recess 27. The door is made with a protruding boxed portion 28 to accommodate the phone, because of the fact that the cabinet cannot ordinarily be made deep enough, owing to the limited space available between walls. A spring-pressed latch 29 is provided on the door for cooperation with a keeper 30 in the cabinet and is arranged to be released by depression of a button 31 as the door is being opened by means

of the handle 32 provided preferably just below the button 31. The seat panel 23 is arranged to be swung out in the opening of the door, and, while it is obvious that there are various ways of interconnecting the door and seat to secure the desired operation, I have illustrated an arm 33 pivoted at its upper end within the cabinet to the side wall 15, as at 34, and pivotally connected at its lower end, as at 35, with a link 36 pivotally connected to the seat panel 23 at 37. The arm 33 is arranged to oscillate between the positions shown in Figs. 1 and 2, and, in the opening of the door, the arm is swung from the retracted position of Fig. 1 to the extended position of Fig. 2 by means of a link 38, which is pivotally connected to the door 22 under the shelf 26, as at 39, and has a lost motion pivotal connection with the arm 33 intermediate the ends of the latter by means of an eye 40 on the arm received in a slot 41 provided in the link. When the cabinet is closed, the link 38, as shown in Fig. 5, receives the eye 40 in the outer end of the slot 41, and, hence, the moment the door is moved in opening, the link 38 communicates movement to the arm 33 to swing the seat panel 23 outwardly. The seat panel 23 is limited in its movement by the engagement of the lower end thereof with stops 42 provided inside the cabinet at the opposite sides 15 and 16, and in its limit position, the panel is substantially horizontal and the link 36 is in a straight line with the arm 33, so that the panel is supported by the stops 42 on one side of the pivot point 25 and on the other side by the arm and link. In that way the seat is made quite rigid. The door 22, by reason of the slot 41 in the link 38, is free to swing independently of movement of the seat panel between the full line and dotted line positions shown in Fig. 4. This latitude for movement is of advantage from the standpoint that the door can be swung out of the way in sitting down or rising from the seat and can be swung toward the person seated, so as to make it unnecessary to remove the phone from the shelf, without making it the least bit awkward to talk into the phone. The hinges 24 for the door are preferably stop hinges which positively limit the swinging of the door so that it cannot strike the wall. A counter-weight 43 is provided on the inside of the seat panel at the lower end thereof, heavy enough to permit the seat panel to swing up and down without a jar, and also facilitate the operation of the panel with the door. In passing, it will be observed that the wire 44 extending from the phone to the box 18 is suitably threaded through eyelets 45 provided within the cabinet on the top wall 13. In this way the extra length of wire that might otherwise get caught behind the door or panel, is disposed of and there is nothing to interfere with the opening and closing of the cabinet.

In operation, when the phone is to be used, the door 22 is opened by means of the handle 32, the button 31 being pressed so as to release the latch 29. As the door is swung open, the seat panel 23 is swung out to the position shown in Fig. 2, its movement being counter-balanced by the weight 43 so as to prevent the seat from dropping with a jar. The person sitting down will swing the door out of the way and after he is seated will swing the door toward him until the phone is situated handily for use. In closing the cabinet, it is only necessary to close the door, because the seat panel will be closed automatically in the movement of the door. It has been found that when the counter-weight 43 is made sufficiently heavy it will tend to accelerate the motion of the seat panel enough to attend to the closing and latching of the door, in the event the door is not fully closed by hand. As a matter of fact, it is possible to close the cabinet by simply lifting up on the outer end of the seat panel to start the same, and thereafter, if the weight 43 is heavy enough, it is found that the panel will close quickly enough to close and latch the door. Rubber bumpers 46 are suitably provided within the cabinet on opposite sides for engagement by the seat panel, to limit the movement thereof and make the closing of the cabinet quiet. When the cabinet is closed it presents a neat and attractive appearance and the phone together with the telephone directory and the phone box are concealed and out of the way.

It is believed the foregoing description conveys a clear understanding of the objects and advantages of my invention. The appended claims have been drawn with a view to covering all legitimate modifications and adaptations.

I claim:

1. In a wall cabinet of the class described, the combination with a cabinet having the front thereof open, of a door hinged on a vertical axis on one side of the cabinet serving as a closure for the upper portion of the open front of the cabinet, a panel serving as a closure for the lower portion of the open front of the cabinet below the door, the same being hinged at opposite sides of the cabinet for swinging movement on a substantially horizontal axis and being arranged when swung out to serve as a seat, and means interconnecting the door and seat panel whereby the same operate together and the movement of the one communicates movement to the other in the opening and closing of the cabinet.

2. In a cabinet for a telephone or the like, the combination with a cabinet, the front of which is open, of a door serving as a closure for the upper portion of the open front of the cabinet, the same being hinged for swinging movement relative to the cabinet on

5 a substantially vertical axis and having means on the inside thereof for supporting a telephone thereon for swinging movement with the door, a seat serving as a closure for the lower portion of the open front of the cabinet below the door, the same being hinged for swinging movement relative to the cabinet on a substantially horizontal axis, and means interconnecting the door and seat whereby the same operate together and the 10 movement of the one communicates movement to the other in the opening and closing of the cabinet.

15 3. A cabinet as set forth in claim 2 wherein in the last mentioned means comprises an arm pivotally connected to the seat at a point above the hinge support for the latter and extending upwardly therefrom toward the door and pivoted to the side wall of the cabinet, and a link pivoted to the door and 20 extending inwardly therefrom and pivotally connected with the aforesaid arm in such a way that swinging movement of the door communicates oscillatory movement to the link whereby to communicate swinging movement to the seat, or vice versa.

25 4. A cabinet as set forth in claim 2 wherein in the last mentioned means comprises an arm pivoted to the side wall of the cabinet at its upper end behind the door and extending 30 downwardly, a link pivotally connected with the seat at a point above the hinge support of the latter and having pivotal connection with the lower end of said arm, whereby oscillatory movement of the arm is 35 arranged to cause swinging movement of the seat, or vice versa, and a link pivotally connected to the door at one end and extending inwardly therefrom and pivotally connected 40 at its other end with the arm intermediate the ends of the latter.

45 5. A cabinet as set forth in claim 2 wherein in the last mentioned means comprises an arm pivoted to the side wall of the cabinet at its upper end behind the door and extending 50 downwardly, a link pivotally connected with the seat at a point above the hinge support of the latter and having pivotal connection with the lower end of said arm, whereby oscillatory movement of the arm is arranged 55 to cause swinging movement of the seat, or vice versa and a link pivotally connected to the door at one end and extending inwardly therefrom and pivotally connected at its other end with the arm intermediate the ends 60 of the latter, the pivotal connection at one end of said last mentioned link being constructed for lost motion permitting a certain amount of swinging movement of the door independently of movement of said arm, whereby to allow the door to swing outwardly away from the seat or inwardly toward the seat when the latter is lowered.

65 6. In a wall cabinet for a telephone or the like, the combination with a shallow housing

open at the front and arranged to be mounted in a wall, the same being arranged to have the phone box mounted therein, a door serving as a closure for the upper portion of the open front of said housing, the same being hinged for swinging movement relative to the housing on a substantially vertical axis and having a housing thereon, a phone shelf in one of said housings, a seat serving as a closure for the lower portion of the open front of the first housing, the same being hinged for swinging movement relative to the housing on a substantially horizontal axis, and means interconnecting the door and seat whereby the same operate together and the movement of the one communicates movement to the other in opening and closing.

7. In a wall cabinet of the character described, the combination with a cabinet open at the front, a door hinged in the upper portion of the open front of the cabinet to swing on a substantially vertical axis, and a panel hinged in the lower portion of the open front of the cabinet for swinging movement on a substantially horizontal axis, of an arm pivoted at its upper end on the side wall of the cabinet behind the hinge support for the door and arranged to oscillate in a fore and aft plane relative to the open front of the cabinet, and means pivotally connecting said arm with the panel, whereby as the latter is swung relative to the cabinet the arm is given oscillatory movement, and a link pivotally connected with the door at one end at a point spaced with reference to the hinge support thereof and at its other end having pivotal connection with the arm intermediate the ends of the latter.

8. In a cabinet for a telephone or the like, the combination with a cabinet, the front of which is open, of a door serving as a closure for the upper portion of the open front of the cabinet, the same being hinged for swinging movement relative to the cabinet on a substantially vertical axis and having means on the inside thereof for supporting a telephone thereon for swinging movement with the door, a seat serving as a closure for the lower portion of the open front of the cabinet below the door, the same being hinged for swinging movement relative to the cabinet on a substantially horizontal axis, and means interconnecting the door and seat whereby the same operate together and the movement of the one communicates movement to the other in the opening and closing of the cabinet, said means being constructed to provide a certain amount of lost motion in the connection between the door and seat, whereby to allow the door to swing outwardly away from the seat or inwardly toward the seat when the latter is lowered.

9. In a wall cabinet of the class described, the combination with an open front cabinet, of a door hinged at one side of the cabinet to

swing outwardly relative thereto on a substantially vertical axis, a seat panel serving as a closure for the cabinet below the door and trunnioned at opposite sides thereof near its lower end for outward swinging movement with reference to the cabinet on a substantially horizontal axis, the same serving as a seat when opened to a position extending substantially horizontally from the cabinet, 10 mechanism interconnecting the door and seat panel whereby the seat panel is arranged to be swung outwardly in the opening of the door, and vice versa, and a counter-weight on the lower end of the seat panel spaced 15 from the trunnions thereof and serving to counter-balance the panel in the opening thereof.

In witness of the foregoing I affix my signature.

20 CHARLES F. THOLIN.
